UNITED STATES PATENT OFFICE.

JAMES H. SPARKS, OF CHICAGO, ILLINOIS.

DESIGN FOR A SHOE.

SPECIFICATION forming part of Design No. 33,118, dated August 28, 1900.

Application filed August 7, 1900. Serial No. 26,200. Term of patent 14 years.

To all whom it may concern:

Be it known that I, JAMES H. SPARKS, a citizen of the United States, and a resident of Chicago, in the county of Cook and State of Illinois, have invented and produced a new and original Design for a Shoe, of which the following is a full, clear, and exact description.

Reference is to be had to the accompanying drawings, forming a part of this specification, in which—

Figure 1 is an elevation showing one side of a shoe embodying my design, and Fig. 2 is an elevation showing the opposite side of a shoe embodying my design.

The leading feature of my design for a shoe consists in extending the fastening-line in a compound curve across the instep, with the two ends terminating at opposite sides of the

front center line of the shoe. Referring particularly to the drawings, the fastening-line extends down from the top of the shoe in a curve toward and across the instep and then downward in an opposite curve, and at each side of the fastening-line an ornamental border is shown.

Having thus described my invention, I claim as new and desire to secure by Letters Patent—

The design for a shoe, as herein shown and described.

In testimony whereof I have signed my name to this specification in the presence of two subscribing witnesses.

JAMES H. SPARKS.

Witnesses:

JOHN W. SIMPSON,
ALLEN G. HIGHSMITH.
